[57] CLAIM

The ornamental design for an animal trap spring compressor, as shown.

DESCRIPTION

FIG. 1 is a right side elevational view of an animal trap spring compressor, showing my new design;
FIG. 2 is a left side elevational view thereof;
FIG. 3 is a front elevational view thereof;
FIG. 4 is a rear elevational view thereof;
FIG. 5 is a top plan view thereof;
FIG. 6 is a bottom plan view thereof; and,
FIG. 7 is a perspective view thereof.
